UNITED STATES PATENT OFFICE.

SVEND E. JOHANNESSEN, OF PITTSFIELD, MASSACHUSETTS, ASSIGNEE TO GENERAL ELECTRIC COMPANY, A CORPORATION OF NEW YORK.

TRANSFORMER.

1,304,184.

Specification of Letters Patent. Patented May 20, 1919.

Application filed November 11, 1915. Serial No. 60,849.

To all whom it may concern:

Be it known that I, SVEND E. JOHANNESSEN, a citizen of the United States, residing at Pittsfield, in the county of Berkshire, 5 State of Massachusetts, have invented certain new and useful Improvements in Transformers, of which the following is a specification.

My invention relates to transformers, 10 more particularly to obtaining greater security against failures thereof.

One of the classes of failures of transformers to be most carefully guarded against is that of puncture or breakdown between the high and low voltage windings. Such 15 failures result in much higher potentials on the normally low voltage sides of the systems than contemplated in the design of the low voltage apparatus connected thereto, and not only is such apparatus thus endangered but life itself may be endangered. Now the terminals or line leads of the windings, or the parts of the windings immediately adjacent the line leads, seem particularly 20 subject to breakdowns; one reason for this is that various disturbances entering the winding from the lines, produce abnormal potentials at these points. Heretofore the line leads of each winding have been located as far apart as possible with a view 25 to economizing the insulation material, since normally the greatest difference in potential in any winding exists between its terminals. This practice however, I have found, often 30 brings the terminals of one winding so close to the other winding that breakdowns originating at one terminal are made direct to, or are communicated to, the other winding.

A particular object of my invention is to 35 so relocate the leads in transformers of multilayer coils, particularly the leads of the high voltage windings, as to minimize this danger. I do this by connecting the terminals of, say, the high voltage winding to such layers of that winding as are separated 40 from the low voltage winding by another or other layers of the high voltage winding. The low voltage winding is thus located adjacent parts of the high voltage winding of 45 lower normal potential than heretofore, is separated by the inductance of those other layers of the high voltage winding from surges on the high voltage lines, and is as it were, further insulated from the poten-

tials of the high voltage terminals by those other layers.

In the accompanying drawing I have illustrated a transformer embodying my invention. Figure 1 illustrates the transformer in perspective; Fig. 2 represents a section 60 of this transformer, one section of the core being omitted for clearness; and Fig. 3 shows diagrammatically the arrangement of the windings and terminals.

In the following detailed description and 65 claims, I shall for convenience and clearness refer to primary and secondary windings. It will be understood, however, that either winding may be primary and the other correspondingly the secondary winding, and that my invention is not limited by this use of these terms except as herein indicated.

The middle core leg 5 of the transformer illustrated is surrounded by the windings. 75 The primary winding comprises the two concentric cylindrical, multilayer coils 6 and 7. The layers of these coils are wound in the direction of the axis of the coils; that is, the terminal layer of the coil 6 proceeds 80 from the line lead 8 to the bottom turn 9, and from thence the conductor passes to the bottom turn 10 and back to the top of the coil at the turn 11, the coils being indicated in Fig. 3 by small circles and the 85 course of current between the various turns by lines joining the circles. The upper turn 22 of the outer layer of the coil 6 is connected at 16 to the upper turn 23 of the inner layer of the coil 7. At each side of 90 the primary winding 6-7 is a concentrically located coil 17 and 18 comprising the secondary winding. These two coils are likewise joined in series, by the connection 19, and are provided with line leads 20 and 95 21 as indicated.

It will be seen from the drawing that the coils 6 and 7 comprise the high voltage winding of this transformer and that the line leads for this winding leave this 100 winding at the center layers thereof. Any breakdown within the high voltage winding adjacent either line lead 8 or 12 is necessarily confined within the high voltage winding itself, and is separated from the secondary winding by certain layers of the primary winding. Thus a breakdown occurring at the point where the terminal 8 enters the

coil 6, or taking place anywhere within the terminal layer 8-9 of this coil which are the places in which a breakdown is most likely to occur, is separated from the coil 18 by the primary layer 10-11 and the layers to the left thereof, beside being separated from the secondary coil 17 by the primary coil 7. Similarly any breakdown adjacent the line lead 12 is separated from the low voltage coils 17 and 18.

While I have described the principle of my invention and the best mode I have contemplated for applying this principle, other modifications will occur to those skilled in this art and I aim in the appended claims to cover all modifications which do not involve a departure from the spirit and scope of my invention.

What I claim as new and desire to secure by Letters Patent of the United States, is,—

1. A transformer comprising adjacently located multilayer secondary and primary windings, each line lead for both of said windings being connected to a layer of its respective winding which is separated from all layers of the other winding by other layers of the same winding.

2. A transformer comprising a high voltage multilayer cylindrical winding, and a low voltage winding including a concentrically located coil at each side of the high voltage winding, each line lead for the high voltage winding being tapped into a layer thereof which is separated from the low voltage coils on both sides thereof by other layers of said high voltage winding.

In witness whereof I have hereunto set my hand this 10th day of November, 1915.

SVEND E. JOHANNESEN.
